GUSTAV A. KRUTTSCHNITT, OF NEWARK, NEW JERSEY.

DESIGN FOR A MEMORANDUM-BOOK COVER.

SPECIFICATION forming part of Design No. 30,602, dated April 25, 1899.

Application filed March 24, 1899. Serial No. 710,380. Term of patent 31 years.

To all whom it may concern:

Be it known that I, GUSTAV A. KRUTTSCHNITT, a citizen of the United States, residing at Newark, in the county of Essex and State of New Jersey, have invented and produced a new and original Design for a Memorandum-Book Cover, of which the following is a specification, reference being had to the accompanying drawings, forming part thereof, and in which—

Figure 1 is a face view of a book-cover bearing and incorporating my design, and Fig. 2 is a longitudinal section of same on the dotted line 2 2 of Fig. 1.

The leading feature of my design consists of the form and ornamental character of the cover, substantially as shown in the drawings.

In the drawings, A B denote the lids of the cover, C designates the back to carry the lids, and D the hinges for the lids.

The lids A B have flat surfaces and are in

line with the horizontal surfaces of the back C, as shown in Fig. 2, and the outer corners of said lids are rounded, as shown in Fig. 1.

The outer surface of the lid A bears the ornamentation illustrated in Fig. 1, the said ornamentation comprising the inner defining border-lines E E and the mottled scroll characters F F, the latter having the appearance of being in relief, though, in fact, presenting a substantially flat surface.

What I claim is—

The design for a memorandum-book cover, substantially as shown and described.

Signed at New York, in the county and State of New York, this 23d day of March, A. D. 1899.

GUSTAV A. KRUTTSCHNITT.
